(57) **CLAIM**

The ornamental design for a medical probe, as shown and described.

DESCRIPTION

FIG. 1 is a front elevational view of a medical probe showing our new design.

FIG. 2 is a rear elevational view thereof.

FIG. 3 is a left side elevational view thereof.

FIG. 4 is a right side elevational view thereof.

FIG. 5 is a top plan view thereof.

FIG. 6 is a bottom plan view thereof; and,

FIG. 7 is a front, right side and top perspective view thereof. The broken lines depict portions of the medical probe that form no part of the claimed design.

1 Claim, 7 Drawing Sheets
